UNITED STATES PATENT OFFICE.

JEFFERSON DIXON HANNAH, OF FAYETTEVILLE, ARKANSAS.

COLLAPSIBLE CRATE.

1,176,546.

Specification of Letters Patent. Patented Mar. 21, 1916.

Application filed January 20, 1914. Serial No. 813,222.

To all whom it may concern:

Be it known that I, JEFFERSON D. HANNAH, a citizen of the United States, residing at Fayetteville, in the county of Washington 5 and State of Arkansas, have invented certain new and useful Improvements in Collapsible Crates; and I do hereby declare the following to be a full, clear, and exact description of the invention, such as will 10 enable others skilled in the art to which it appertains to make and use the same.

This invention is a shipping crate having for its object to provide a coop or crate which can be folded into compact form for 15 return transportation.

It is a purpose of the invention, also, to provide a collapsible crate which is simple, strong and durable, comparatively inexpensive to manufacture, and which can be 20 readily built up and easily folded, the various parts thereof being locked in either the extended or folded positions.

Further objects and advantages will be set forth in the following detailed description, and particularly pointed out in the appended claims.

The embodiment of the invention is illustrated in the accompanying drawings in which:

30 Figure 1 is a perspective view of a crate constructed in accordance with the invention, the crate being shown in its extended position. Fig. 2 is an end view of the crate with the parts partially folded. Fig. 3 is a 35 plan view of the folded crate. Fig. 4 is a detail perspective view showing the locking means for the slidable bar of the cover. Fig. 5 is a detail view of the bottom plate, the top plate and the pivoted clamps comprising 40 the fastening means, removed from the crate. Fig. 6 is a detail view showing one means of locking the side and end members in their extended positions.

Referring more particularly to the accompanying drawings, the base which may be of any suitable material, is indicated at 1 having end members 2 hinged thereto. The end members are preferably of sufficiently thick material to form a support when 50 moved to a vertical position with relation to the base. This thickening may be accomplished by securing extra pieces of material at the top and bottom of the end members such as indicated at 3. Secured along each 55 side of the base 1 is an upstanding strip 4 to which is hingedly mounted a side member

5. These upstanding members 4 permit of the side members 5 to be folded toward the base 1 but into contact with the end members 2 which are confined between the 60 side members 5 and base 1 when the crate is placed in its folded position. A cover 6 is provided for the crate and is movable vertically with relation to the base 1. The end members 2, the side members 5 and the 65 cover are each shown composed of a frame and a plurality of slats, although the crate may be constructed in any other suitable manner. When the side and end members are raised to a substantially vertical position 70 with relation to the base, the cover 6 is adapted to rest upon the upper edges thereof, and to be clamped down against said members to maintain them against movement toward the base. However, if desired, 75 suitable retaining means, such as a hook secured to one member 7, may engage an eye 8 on the other member to maintain the parts in their upright position.

An important feature of the invention resides in the clamping device. Referring more particularly to Figs. 1, 2 and 3, the base 1 is provided with a base plate 9 having upturned ends 10, which are preferably flared outwardly as at 11. If desired, the 80 cover 6 may be provided with a top plate 12 secured thereto. The top plate 12 is preferably provided with means at each end, for example, the eye 13, to receive a clamping rod 14, which is pivoted at 15 to the outwardly flared end 11 of the base plate 9. The rod is adapted to slide within the eye, or its equivalent device 13, as will be explained hereinafter. Mounted on each of the 85 rods 14, there being four illustrated in the drawings, is a bearing plate 16 which is adapted to be brought into engagement with the ends of the cover plate 12, when the 90 crate is in its extended position. When the crate is in its closed position, these bearing plates are adapted to have their edges rest against the cover plate 12, as illustrated in Fig. 3. These bearing plates are preferably provided with upstanding ears 17 to which 95 are pivotally mounted suitable retaining devices. In the drawings, the rods 14 are preferably positioned on opposite sides of the crate, and one of said rods is shown provided with an eye member 18 pivoted to the ears of the bearing plate 16, while the opposite rod 14 is provided with a hooked member 19 pivoted to the ears 17 of the bearing 100

105

110

plate and adapted to engage the eye 18 when the crate is in its folded position, as illustrated in Fig. 3. The upper end of each of the rods 14 may be screw threaded to engage a binding nut 20, which contacts with the bearing plate and holds the parts rigidly in the extended or folded positions, as will be readily understood.

The device is especially designed as a 10 chicken coop, and for this purpose one of the bars 21 of the cover is slidably mounted with relation to the cover, the remaining bars 22 being fixed to the cover. This arrangement permits of the bar 21 to be moved 15 longitudinally with relation to the coop for a considerable distance, to permit of the placing of poultry into the coop or taking them therefrom without the escape of the birds from the opened top.

20 Another important feature of the invention resides in the means to lock the slidable bar against movement. In Fig. 4 this locking device is disclosed as a plate 24 pivoted at 25 to one of the fixed bars 22, and adapted 25 to be positioned in between upstanding lugs 26 secured to the slidable bar 21. The free end of the plate 24 may be provided with an aperture through which is passed an eye 27 on another of the fixed bars 22, and any suitable fastening means, such as a cotter pin 28, may be passed through the eye to retain 30 the plate 24 in engagement with two of said fixed bars, thereby preventing the longitudinal movement of the slidable bar with relation to the coop.

In operation, the ends 2 and sides 5 are raised to the substantial vertical positions, the cover 6 is brought into engagement with the top edges thereof. If retaining devices, 40 such as the hook and eye, 7 and 8, are desired, these devices may be brought into engagement, or the top may hold the sides and ends vertical by frictional engagement therewith. The upward movement of the cover 6 45 permits the sliding engagement of the rods 14 with the eyes 13 of the cover plate 12, after the parts have been raised to their proper assembled position, the bearing plates 16 are forced down against the cover plate 12 by means of the binding nuts 20, whereupon the slidable bar 21 may be moved to 50 close the coop. The bar can then be locked in its closed position by means of the cotter pin 28 engaging the eye to retain the plate 24 in its locked position with relation to bar 21. When the device is in the folded position of Fig. 3, the bars 14 slidably engage the eyes 13 of plate 12 until the hook and eye members 18 and 19, are brought into

locking engagement, whereupon the binding 60 nuts can be moved to draw the opposed bearing plates away from each other, thereby placing tension upon the eye and hook members 18 and 19 respectively.

Having thus described my invention, what 65 I claim as new and desire to secure by Letters Patent is:—

1. A folding crate comprising a base, sides and ends hinged thereto, a cover, a plate secured to the base, another plate secured to 70 the cover, clamping devices pivoted to each end of the base plate and adapted to slidably engage the cover plate when the crate is in its extended position, and means to connect said clamping devices when the crate is in 75 its folded position.

2. In a folding crate, a base plate having upwardly directed ends provided with outwardly turned ears, a clamping rod pivotally mounted to each of said ears, the free end of 80 said clamping rod being threaded and provided with a binding nut, a bearing plate positioned near an end of each rod, and a cover plate having a loop eye secured near each end thereof to permit of slidable movement of the cover plate with relation to the clamping rods. 85

3. A folding crate comprising a base, sides and ends hinged to the base, a detachable cover, and clamping devices to retain the 90 cover in position when the crate is extended or folded, said clamping devices comprising a base plate, a rod pivoted to each end of 95 said base plate, said rods being slidably mounted in means positioned on the cover, a bearing plate slidably mounted near the end of each rod, rod connecting devices carried by said bearing plates, and binding nuts adapted to engage said bearing plates and to place tension on said connecting devices. 100

4. A folding crate comprising a base, sides and ends hinged to the base, a detachable cover, retaining plates mounted on the base and the cover respectively, clamping rods pivoted to each end of the base plate and 105 adapted to slidably engage the cover plate when the crate is in its extended position, a bearing plate carried by each clamping rod, an eye carried by one rod, a hook carried by another rod to engage the eye, and means 110 to impart tension on the hook and eye.

In testimony whereof, I affix my signature, in presence of two witnesses.

JEFFERSON DIXON HANNAH.
